(57) **CLAIM**

The ornamental design for a hook for musical instrument strap, as shown and described.

DESCRIPTION

FIG. 1 is a front perspective view of the hook for musical instrument strap;

FIG. 2 is a front elevation view thereof;

FIG. 3 is a rear elevation view thereof;

FIG. 4 is a side elevation view thereof;

FIG. 5 is a side elevation view thereof from the opposite side of FIG. 4;

FIG. 6 is a top elevation view thereof;

FIG. 7 is a bottom elevation view thereof; and,

FIG. 8 is a front elevation view thereof in use.

The broken lines in FIGS. 1-8 represent the portions of the hook for musical instrument strap which form no part of the claimed design.
